UNITED STATES PATENT OFFICE

MINER F. WETMORE, OF NORWICH, CONNECTICUT, ASSIGNOR TO THE AMERICAN THERMOS BOTTLE COMPANY, OF NORWICH, CONNECTICUT, A CORPORATION OF OHIO

BOTTLE CARRIER

Original application filed July 30, 1927, Serial No. 209,608. Divided and this application filed September 8, 1928. Serial No. 304,655.

This invention is for a bottle carrier particularly adapted for supporting double-walled vacuum bottles in inclined position. In one embodiment of my invention, this carrier comprises a plurality of spaced cross bars connected by driving chains and having rollers arranged to engage supporting rails. Each cross bar carries one or more bottle-supporting members of novel construction.

10 It is well known that double-walled bottles of the vacuum type are provided with tubular extensions at their base, and I utilize these extensions to hold the bottles firmly in position on the supporting members. In a preferred form of my invention, the bottle-supporting members consist of wire loops so shaped as to receive the bottles and engage the tubular extensions thereof in such a way that the bottles cannot slip off the loops.

20 These wire loops are inexpensive to make and easily attached to the cross bars by bending the ends of the loop around screws or bolts.

The novel features and practical advantages of my invention will be understood 25 from a detailed description of the accompanying drawings which illustrate a bottle-carrier as actually constructed and successfully operated. In these drawings—

Fig. 1 shows a side elevation of a portion 30 of the bottle carrier; and

Fig. 2 is a fragmentary view in perspective to show more clearly the bottle-supporting loops.

The carrier is mounted on a pair of end 35 supports 10, only one of which is shown, and each support carries a shaft 12 on which two sprocket wheels 13 are mounted. The two pairs of sprocket wheels 13 carry a pair of endless chains 14 of any practical construction. In the drawings I have shown the chains of the usual link type, which are easily put together to the required length. The 40 wheels 13 are driven at the proper speed by any suitable connections, which it is not necessary to show or describe. It is sufficient to say that one of the shafts 12 is connected to an electric motor or other source of power by suitable speed-reducing gears. Cross bars 15 are connected to the sprocket chains 14 in 45 any practical way. In the present case, the

cross bars 15 consist of angle bars carrying each a pair of blocks 16 to which the driving chains are connected, as by bolts 17 or other fastening members. The blocks 16 also carry shaft extensions 18 on which rollers 19 are mounted. These rollers are arranged to travel over upper tracks 20 and lower tracks 21, which may simply consist of angle irons supported in parallel relation between the end frames 10.

55 The transverse bars 15 are spaced equidistantly and carry a plurality of bottle-supporting members which are so shaped as to receive the bottles and securely hold them in position as they travel from one end of the machine to the other. The bottle supports 21 are preferably shaped each from a single piece of wire, the ends of which are secured to the cross bars 15 by screws or bolts 22. For this purpose, the ends of the wire loops 60 may be bent around the screws or bolts, the heads of which clamp the loop ends to the bar. The bottles 23 held on the supports 21 are of the double-walled vacuum type, and are therefore provided at the base with a 65 tubular extension 24 through which the bottles are exhausted. These tubular extensions engage the tips 25 of the supports 21 and thereby prevent the bottles from falling off. It is only necessary to place the bottles properly 70 on their supports and they are automatically retained in a secure position during their travel, which is in the direction indicated by the arrow α in Fig. 1.

75 Although I have shown and described a specific construction, I want it understood that my invention is not limited to the details set forth. Changes and modifications may be made without departing from the scope 80 of the invention as defined in the appended 85 claims.

This application is a division of my co-pending case, Serial Number 209,608, filed July 30, 1927, in which the carrier mechanism of this invention was fully disclosed and 90 claimed. However, owing to an official requirement of division, the present divisional application was necessary.

I claim as my invention:

1. In a carrier for double-walled vacuum 100

bottles having each a tubular extension at the base, a support, a member mounted on said support and shaped to receive a bottle, said member having a portion adapted to engage said extension, whereby the bottle is supported on said member and held out of engagement with said support.

2. As a means for supporting a double-walled vacuum bottle having a tubular extension, a one-piece open frame shaped to receive a bottle and having a portion arranged to engage said extension, so that the bottle is securely held on said frame with the base of the bottle extending downward.

3. As a means for supporting a double-walled vacuum bottle having a tubular extension, a one-piece wire loop shaped to receive a bottle and having a tip arranged to engage said extension, so that the bottle is securely held on said loop.

4. A bottle carrier comprising a plurality of spaced cross bars, driving means connected to said bars, and a plurality of bottle supports secured to said bars, said supports consisting each of a single piece of wire bent to form a pair of spaced sides between which a bottle is held in an inclined position with the base of the bottle extending downward.

5. A bottle carrier comprising a plurality of spaced cross bars, driving means connected to said bars, a plurality of members secured to said bars for supporting each a double-walled vacuum bottle having a tubular extension, each member having a pair of sides connected by a looped portion adapted to interlock with said extension and thereby hold the bottle in position.

6. In a carrier for double-walled vacuum bottles having each a tubular extension, a plurality of spaced cross bars connected together for movement, and members secured to said bars for supporting each a double-walled vacuum bottle, each member consisting of a one-piece wire loop shaped to receive the bottle and having a tip arranged to engage said extension, so that the bottle is securely held on the loop, the ends of each loop being coiled about a pair of fastening elements carried by the supporting bar.

7. In a bottle-conveying machine, the combination of a pair of upper rails and a pair of lower rails, an endless carrier movably supported on said rails, said carrier comprising a plurality of spaced cross bars having rollers secured to said bars for supporting double-walled vacuum bottles having each a tubular extension, said bottle supports consisting each of a one-piece open frame shaped to receive a bottle and having a portion arranged to engage said extension and thereby securely hold the bottle with the base thereof extending downward.

8. In a bottle-conveying machine, the combination of a pair of upper rails and a pair of lower rails, an endless carrier movably sup-

ported on said rails, said carrier comprising a plurality of spaced cross bars having rollers engaging said rails, a plurality of spaced bottle supports secured to said bars for supporting double-walled vacuum bottles having each a tubular extension, said bottle supports consisting each of a one-piece wire loop shaped to receive a bottle and having a tip arranged to engage said extension, whereby the bottle is securely held on the loop.
